UNITED STATES PATENT OFFICE

2,117,861

EVAPORATOR FOR REFRIGERATING MACHINES

Christian Steenstrup, Schenectady, N. Y., assignor to General Electric Company, a corporation of New York

Application August 29, 1936, Serial No. 98,456

3 Claims. (Cl. 62—126)

My invention relates to evaporators or cooling units for refrigerating machines.

It is an object of my invention to provide an improved evaporator of the flooded type for refrigerating machines, having a header and a plurality of U-shaped depending refrigerant circulating passages and having an improved arrangement for providing a rapid and efficient positive circulation of liquid refrigerant through the passages thereof.

Another object of my invention is to provide an improved evaporator of the flooded type for refrigerating machines which shall provide a positive and efficient circulation of liquid refrigerant with a minimum of turbulence within the header.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 shows a household refrigerator utilizing an evaporator embodying my invention; Fig. 2 is an enlarged perspective view of the evaporator shown in Fig. 1; and Fig. 3 is a plan view of the sheet metal portions of the evaporator shown in Fig. 1 prior to bending.

Referring now to the drawing, in Fig. 1 I have shown a household refrigerator comprising a cabinet 10 having a food compartment 11 and a door 12 for closing the compartment. The compartment 11 is cooled by an evaporator or cooling unit 13 arranged in the upper portion thereof and supplied with refrigerant from a refrigerating machine mounted on the top of the cabinet. The refrigerating machine comprises a closed casing 14 in which is arranged a motor and a refrigerant compressor, an air cooled refrigerant condenser 15 comprising a conduit 16 and a float valve chamber 17. During the operation of the motor and compressor within the casing 14 gaseous refrigerant is compressed and discharged into the conduit 16 of the condenser 15 where it is cooled by air circulating over the condenser due to the natural drafts, and is liquefied. The liquefied refrigerant then flows through a connection 18 to the float valve chamber 17. When a predetermined amount of liquid refrigerant has collected in the chamber 17 a float arranged therein rises and admits refrigerant to the evaporator 13 through a conduit 19. The liquid refrigerant is vaporized by the absorption of heat from the chamber 11, and the vapor collects in

a cylindrical header 20 from which it is withdrawn through a suction conduit 21 and is returned to the casing 14. This cycle of operation continues as long as the compressor within the casing is operating. The temperature within the compartment 11 is regulated thermostatically in the usual manner by controlling the operation of the motor which drives the compressor within the casing 14.

In evaporators of the flooded type it is desirable to provide some arrangement for producing a rapid circulation of liquid refrigerant and a recirculation of liquid refrigerant from the header through the refrigerant circulating passages. An increased rate of circulation of liquid refrigerant increases the rate of absorption of heat and, consequently, provides an evaporator which will cool the surrounding air more rapidly and will also provide for rapid freezing of water, desserts and the like. I attain these advantages by constructing the evaporator of two sheets of metal having indentations formed therein to provide a header and a plurality of depending U-shaped refrigerant circulating passages or conduits and an arrangement whereby the refrigerant supplied to the evaporator is utilized to produce a positive circulation of liquid refrigerant to the header and a recirculation from the header in a predetermined direction. Portions of the U-shaped refrigerant passages are preferably arranged in a horizontal plane to provide a surface for supporting freezing trays which afford rapid freezing of water, desserts and the like.

Referring now to Fig. 2, the evaporator 13 is made of inner and outer sheet metal portions 22 and 23 respectively. The sheets 22 and 23 are made of stainless steel or other suitable material and are provided with indentations or corrugations forming the cylindrical header 20 adjacent the upper ends of the sheets, a plurality of separate U-shaped depending conduits 25, a sinuous conduit 26, a manifold 27 and a plurality of ducts 28 connected to the manifold 27 and the lower portions of the U-shaped passages 25. The upper ends of the U-shaped passages all communicate with the lower portions of the header 20 and are all arranged substantially in longitudinal alignment. The sheets 22 and 23 are bent to form side walls 29 and 30 and top and bottom walls 31 and 32 respectively, providing upper and lower surfaces 31a and 32a for supporting freezing trays and the like. Depending U-shaped refrigerant circulating passages 25 extend downwardly from the header 20 within the side wall 29 and across the bottom wall 32, and

the sinuous conduit 26 extends in part across the top wall 31 and in part within the side wall 30. The sheets 22 and 23 are secured together around their edges and between the indentations by welding, brazing or any other suitable manner; the front and rear edges of the sheet 22 being folded over the respective edges of the sheet 23 in the manner indicated at 24. A flange 33 formed on the sheet 22 at the end thereof remote 5 from the header 20 fits against the side wall 29 and is welded or otherwise secured thereto. A metal sheet 34 is welded to the upper end of the side wall 30 and constitutes a side wall for an upper freezing chamber. The wall 29 and the 10 wall 34 are provided with flanges 35 and 36 respectively, for securing the evaporator to a removable top wall of a refrigerator cabinet. The general arrangement of the header and the 15 passages within the wall of the evaporator is not 20 my invention but is the invention of Leonard W. Atchison, and is disclosed and claimed in his pending application, Serial No. 51,846, filed November 27, 1935, and assigned to General Electric Company, the assignee of my present invention. I do not, therefore, herein claim any invention claimed in the said Atchison application.

Referring now to Figs. 2 and 3, liquid refrigerant is admitted to the evaporator 13 through the conduit 19 and enters a passage 31 formed 30 in the side wall 29 and the bottom wall 32. The passage 31 communicates directly with the sinuous passage 26 and the refrigerant therefore flows into the sinuous passage, circulates therethrough and flows to the manifold 27.

35 The ducts 28 which convey the refrigerant uniformly from the manifold 27 to the several U-shaped passages 25 are arranged in such manner as to induce a positive circulation of liquid refrigerant in a predetermined direction 40 through each of the U-shaped passages. In order to accomplish this mode of circulation each of the ducts 28 is arranged to inject refrigerant directly and longitudinally into one leg of a U-shaped passage, to produce a flow through 45 that leg of the passage and upwardly to the header 20. The resultant injector action produces a positive flow of liquid refrigerant through each of the U-shaped passages, liquid refrigerant recirculating from the header downwardly 50 through the other leg of the passage; a rapid circulation and recirculation in all U-shaped passages is thereby provided. In order to minimize the turbulence of the liquid refrigerant within the header 20 which results from the 55 rapid circulation of refrigerant, I arrange the injectors 28 so that the same direction of flow of liquid refrigerant obtains in adjacent legs of adjacent U-shaped conduits. It is evident that when the refrigerant is thus caused to circulate 60 in the same direction in the pairs of adjacent legs of the U-shaped passages, there will be a less frequent reversal of the direction of flow of refrigerant along the header. If the direction of flow were made the same in all the 65 U-shaped passages, each passage would have refrigerant flowing therein in a direction opposite the direction of flow in the adjacent passage and there would be increased turbulence and consequently increased resistance to the circulation 70 of liquid refrigerant. In the evaporator, as described above, there will be larger areas of upward and downward flow, since each area will correspond to the portion of the header above two of the legs of the U-shaped passages.

75 During the operation of the evaporator de-

scribed above, refrigerant is admitted to the passage 31 from the passage 19 and flows from the passage 31 through the sinuous conduit 26 and thence to the manifold 27. Some of the refrigerant flowing through the conduit 26 is vaporized by the absorption of heat from the air within the chamber 11 and from articles placed on the freezing shelf 31a. The vaporized and liquid refrigerant flows from the manifold 27 in substantially equal amounts through the ducts 28 10 and into the several U-shaped passages 25. Since each of the ducts 28 directs refrigerant upwardly into only one leg of the U-shaped passage with which it communicates, the direction of flow of refrigerant in each U-shaped 15 passage is definitely predetermined and minimum turbulence of liquid refrigerant in the header is assured at all times. Liquid refrigerant vaporized within the passages 25 by the absorption of heat from articles resting on the shelf 32a 20 and from the air within the chamber 11, collects in the header and is withdrawn therefrom through suction conduit 21.

It will be apparent from the foregoing that I have provided a flooded evaporator of simple 25 construction having an improved arrangement for predetermining the direction of flow of refrigerant in the circulating passages thereof and for assuring a minimum of turbulence and, therefore, a minimum resistance to circulation 30 of the liquid refrigerant.

While I have described my invention in connection with a household refrigerator, other applications will readily be apparent to those skilled in the art. I do not, therefore, desire my invention to be limited to the particular construction shown and described, and I intend in the appended claims to cover all modifications within the spirit and scope of my invention.

What I claim as new and desire to secure 40 by Letters Patent of the United States is:

1. A flooded evaporator for refrigerating machines comprising a header and a plurality of separate depending U-shaped refrigerant circulating passages, both of the ends of each of said passages communicating with said header and all of the ends of said passages being substantially in longitudinal alignment along said header, means including a plurality of ducts one communicating with the lower portion of each of said U-shaped passages and injecting liquid refrigerant longitudinally into said U-shaped passages for producing a circulation of liquid refrigerant toward said header in one leg of each of said passages and away from said header in the other leg of each of said passages and for determining the direction of circulation of liquid refrigerant in each of said passages, and means for withdrawing gaseous refrigerant from said header.

2. A flooded evaporator for refrigerating machines comprising a header and a plurality of separate depending U-shaped refrigerant circulating passages, both of the ends of each of said U-shaped passages communicating with said header and all of the ends of said U-shaped passages being substantially in longitudinal alignment along said header, means including a plurality of ducts of relatively small cross-sectional area as compared with the cross-sectional area 70 of said passages and injecting liquid refrigerant longitudinally into one leg of each of said passages for producing a circulation of liquid refrigerant toward said header through said one leg and away from said header in the other of 75

said legs, and means for withdrawing gaseous refrigerant from said header.

3. A flooded evaporator for refrigerating machines comprising a header and a plurality of separate depending U-shaped refrigerant circulating passages, both of the ends of each of said passages communicating with said header and all of the ends of said passages being substantially in longitudinal alignment along said header, means communicating with the lower portion of each of said U-shaped passages and injecting liquid refrigerant longitudinally into said U-shaped passages for producing a circu-

lation of liquid refrigerant toward said header in one of the legs of each of said passages and away from said header in the other leg of each of said passages and for determining the direction of circulation of liquid refrigerant in each of said passages, said circulation producing means being arranged to circulate the liquid refrigerant in the same direction in adjacent legs of adjacent ones of said U-shaped passages, and means for withdrawing gaseous refrigerant from said header. 5 10

CHRISTIAN STEENSTRUP.
